Company, Cleveland, Ohio, a corporation of
Ohio

Application May 11, 1948, Serial No. 26,305

30 Claims. (Cl. 103—46)

1

My invention relates in general to apparatus for pumping fluids from wells and, more particularly, to an apparatus which includes a reciprocating pump of the fluid operated type, a primary object of the invention being to provide an apparatus of this character having means associated therewith for absorbing fluid pressure variations which may impose hydraulic shock loads on the system.

Fluid operated pumps are used extensively in the oil industry for pumping oil from wells and are well known in the art so that a detailed description thereof herein is unnecessary, an example of such a pump being disclosed in my Patent No. 2,134,174, issued October 25, 1938. Briefly, such a fluid operated pump comprises a motor section and a pump section and is set in the well at the level from which oil is to be pumped. A power tubing for conveying operating fluid under pressure to the pump and a production tubing for conveying oil and other fluids discharged by the pump to the surface are connected to the motor and pump sections, respectively. The operating fluid is usually clean crude oil and will be referred to hereinafter as the power oil. For convenience, the combination of fluids pumped, which may include oil, water, etc., will be referred to hereinafter as the production fluid.

The motor section of the pump includes a cylinder having a piston therein and includes a suitable engine valve mechanism for admitting the power oil alternately to opposite ends of the motor cylinder so as to reciprocate the motor piston. The pump section includes a cylinder having a piston therein which is connected to the motor piston so that the reciprocatory motion of the motor piston is communicated to the pump piston. The latter draws fluid from the well and discharges it into the production tubing through suitable intake and exhaust valve mechanisms. Fluid operated pumps normally used in the oil industry are of the double acting type so that as well fluid is drawn into one end of the pump cylinder during a given stroke of the pump piston, well fluid drawn into the opposite end thereof during the preceding stroke is simultaneously discharged into the production tubing.

In order to prevent excessive wear and possible breakage of the various parts of a pump of this type, and in order to prevent possible damage to other components of the installation in which the pump is incorporated, it is essential to minimize any shock loads which may originate in the pump, the provision of an apparatus for absorbing such shock loads being the primary object of the present invention. Shock loads may be developed in the pump under various conditions of operation, one of these being the condition resulting when the load on the pump piston decreases suddenly due, for example, to the presence of air or gas in

2

the pump cylinder. The fluid entering the well casing from an adjacent oil producing formation may contain considerable quantities of natural gas, the amounts present depending upon the amounts present in the formation and depending upon prevailing conditions of pressure, temperature, etc. Sudden decreases in the load on the pump piston may also result if the well is operated beyond its capacity so that air or gas is drawn into the pump cylinder as a result of the fluid level being drawn below the pump inlet. In some instances, the well casing may be connected to a vacuum line so that the pressure on the gas may be less than atmospheric. Also, in fields subjected to partial vacuums, air may be drawn into the well casing if it is left open.

Since the pump piston reduces the pressure in the pump cylinder below that prevailing in the well as it draws well fluid into the pump cylinder, any gas present in the well fluid in solution or in suspension may be liberated in the pump cylinder with the result that a quantity of liquid sufficient only to partially fill the pump cylinder is drawn thereinto, the balance of the pump cylinder being filled with gas. Similarly, the pump cylinder may be partially filled with air or gas at a low pressure if the well is pumped beyond its capacity. Consequently, when the direction of movement of the pump piston is reversed, the pump piston acts only on the air or gas in the pump cylinder for at least a portion of the stroke. Since the air or gas is highly compressible, it offers but little resistance to movement of the pump piston so that the motor and pump pistons, being directly connected, may accelerate to an extremely high speed. In many instances, the speed attained by the pistons may greatly exceed their normal operating speed, the reason for this being that a considerable amount of potential energy is normally stored in the power oil supply system at the pressures usually employed because of the compressibility of the column of power oil in the power tubing and the expansibility of the power tubing. Such potential energy is released when the load on the pump piston decreases and may accelerate the motor and pump pistons to a speed far in excess of their normal operating speed.

When the pump piston, moving at an abnormally high speed, strikes liquid in the pump cylinder, severe shock loads are developed which may cause extensive damage to the pump in the form of excessive wear, scoring, seizing and even breakage of parts. Moreover, pressure surges of considerable magnitude may be produced in the power oil and production fluid columns above the pump and may result in abnormal stressing of and possible damage to other components of the system. Also, if the well fluid being pumped contains a large percentage of water, which is frequently the case, shock loads originating in the

pump may be particularly severe, the reason for this being that the compressibility of water is less than that of crude oil. Consequently, when water is present, the compressibility of the production fluid column above the pump is materially reduced, as compared to the compressibility of a production fluid column consisting of relatively pure crude oil, or a mixture of crude oil and gas, so that the amount of energy which it is capable of absorbing is materially decreased. Also, if air is drawn into the pump under shock loading conditions with water present, both mechanical failure and corrosion are greatly accelerated for two reasons: first the presence of oxygen reduces the fatigue strength of the material; and, second, the high stresses produced by shock loads increase the chemical action at points of maximum stress.

A governor located in close proximity to the pump may be employed to reduce the rate of flow of power oil to the motor section of the pump in response to decreases in the load on the pump piston so as to reduce the piston speed which would otherwise be attained, an example of such a governor being disclosed in my Patent No. 2,311,157, issued February 16, 1943. However, due to the fact that such a governor tends to operate only after the condition which results in acceleration of the motor and pump pistons has already developed, there may be some lag in its operation. Consequently, even if a governor is employed, shock loads of undesirably large magnitude may be produced, although such shock loads are, of course, greatly reduced as a result of the use of the governor.

Even when a fluid operated pump of the type disclosed in my Patent No. 2,134,174, for example, is operating under normal conditions, i. e., when little or no gas or air is present in the well fluid being pumped, pressure pulsations are produced in both the power oil and the production fluid columns due to the fact that the motor and pump pistons stop momentarily at the ends of their stroke. This results in an increase in the pressure of the power oil and a decrease in the pressure of the production fluid. The amount of dwell at the ends of the stroke may be controlled with an engine valve of the type disclosed in my Patent No. 2,134,174, it being desirable to have sufficient dwell to allow time for the pump valves to seat. If the time allowed for the pump valves to seat is too great, excessive pressure pulsations in both the power oil and production fluid columns result, and, if the time allowed is too small, serious pressure pulsations in the production fluid column result. It is impractical and, in many instances, impossible to eliminate such pressure pulsations by regulating the time allowed for the pump valves to seat. Although the magnitude of such pressure pulsations is small when the pump is operated at moderate speeds and when the pump cylinder fills properly, such pressure pulsations may be sufficiently large to cause serious difficulties at high pump speeds. Severe stresses may be developed in various components of the installation by the pulsations if the frequency of the reciprocatory motion of the motor and pump pistons coincides with either the natural frequency of oscillation or one of the harmonics of either the power oil or the production fluid columns above the pump, i. e., if the frequency of the pressure pulsations developed in the columns as a result of the reciprocatory motion of the motor and pump pistons coincides with either the natural frequency or one of the harmonics of one of the columns. These columns are only moderately damped so

that standing pressure waves of a magnitude sufficient to develop abnormal stresses in various components of the installation may be produced under such resonant operating conditions.

Since the natural frequencies of the power oil and production fluid columns are usually relatively low as compared to the frequency of reciprocation of the motor and pump pistons during normal operation, it is usually possible to avoid operating the pump in phase with the natural frequencies of the columns. However, it is virtually impossible to select an operating speed for the pump which avoids both the natural frequencies of the power oil and production fluid columns and all of the harmonics thereof due to the fact that the intervals between the natural frequencies and the first harmonics and the intervals between harmonics are relatively small. Another factor which makes it difficult to avoid both the natural frequency and all of the harmonics of the production fluid column in particular is that the natural frequency of this column varies with variations in the proportions of gas, oil and water in the production fluid. Consequently, since resonant operating conditions cannot be avoided readily by a selection of a suitable operating speed for the pump, it is desirable to reduce the magnitude of the pressure surges resulting from the reciprocatory nature of the operation of the pump so as to avoid producing standing pressure waves of excessive magnitude, the provision of an apparatus capable of absorbing such pressure surges being an important object of the present invention.

In fluid operated pump installations of the type under consideration, the power oil and production fluid columns are semiclosed systems and do not communicate with each other freely in both directions because the fluid operated pump is interposed between them, the direction and amount of communication possible depending upon the positions of the engine and pump valves. With closed columns each terminating in a valve, serious "water hammer" may result from sudden closing of the valves with high fluid velocities. In all cases of normal operation and some cases of shock resulting from malfunctioning of the pump valves or improper filling of the pump cylinder, the pressure surges in the two columns are out of phase and may be cancelled out or greatly reduced by balancing the two columns against each other, which is another important object of my invention.

More specifically, an object is to provide a shock absorber which includes a movable fluid separating means, such as a piston, having opposed first and second surfaces which are exposed to the fluid pressures obtaining in the power tubing and the production tubing, respectively. With this construction, an increase in the pressure of the fluid in one of the tubings results in movement of the piston, or other fluid separating means, so that the fluid in the other tubing is compressed, whereby the energy producing such movement of the piston is absorbed.

Another object is to provide a shock absorber of the foregoing character wherein the piston is provided with a third surface which is exposed to a different fluid pressure, the fluid acting on the third surface of the piston, which fluid is referred to hereinafter as the third or shock absorbing fluid, being confined so that it is compressed during movement of the piston in one direction and thus absorbs the energy producing such movement of the piston.

My invention utilizes the principle that the amount of energy absorbed by a liquid as it is compressed is a function of the pressure of the liquid, an important object of the invention being to provide a shock absorber wherein the third or shock absorbing fluid is a liquid maintained at a very high pressure.

Another important object is to provide a shock absorber which includes pumping means for maintaining the pressure of the shock absorbing liquid at the desired value. A related object is to provide a pumping means which is carried by the shock absorber piston. Still another object in this connection is to provide such a pumping means which is fluid operated and which communicates with one end of the motor cylinder of the fluid operated pump so that as power oil is periodically admitted into said one end of the motor cylinder to operate the pump, it also operates the pumping means carried by the shock absorber piston.

Other objects of the invention are to provide a shock absorber which may be connected directly to a pump with which it is to be used so that the piston therein may be exposed to the fluid pressures obtaining in the power tubing and the production tubing at points in close proximity to the pump, whereby pressure surges originating in the pump are absorbed substantially instantaneously, and to provide a compact device which occupies a minimum of space in a well.

The foregoing objects of my invention and the advantages suggested thereby, together with various other objects and advantages which will become apparent, may be attained through the employment of the exemplary embodiment which is illustrated in the accompanying drawings and which is described in detail hereinafter. Referring to the drawings:

Fig. 1 is a vertical sectional view illustrating a pumping installation which embodies the invention as installed in a well;

Fig. 2 is an enlarged, vertical sectional view taken along the broken line 2—2 of Fig. 1 and showing an upper portion of a shock absorber of the invention;

Fig. 8 is a transverse sectional view taken along the broken line 8—8 of Fig. 5; and

Fig. 9 is a graph illustrating the operation of the shock absorber.

Referring particularly to Fig. 1 of the drawing, I show a well casing 10 which extends downwardly from a casing head 11 into an oil producing formation 12 of a well, the lower end of the casing being provided with perforations 13 through which well fluid, i. e., oil, water, gas, etc., from the oil pro-

ducing formation may flow into the casing. A production tubing 14 is suspended from a tubing head 15 which forms an intermediate part of the casing head 11 and extends downwardly through the casing 10 into a body 16 of well fluid in the lower portion thereof. The lower end of the production tubing 14 is equipped with a pump seat 17 which is adapted to receive and support the inlet end 18 of a fluid operated pump 19. A power tubing 20 for conveying power oil to the pump 19 is suspended from a cap member 21 of the tubing head 15 and extends downwardly through the production tubing 14. In the particular construction illustrated in the drawings, the power tubing 20 is connected to the pump 19 through a shock absorber or cushioning device of the invention which is indicated generally by the numeral 22 and is described in detail hereinafter.

The fluid operated pump 19 per se forms no part of the present invention and is not shown in complete detail in the drawings. The pump 19 may, for example, be of the type disclosed in my aforesaid Patent No. 2,134,174, or may be of any other suitable type, as is well known in the art. As best shown in Fig. 1 of the drawings, the pump 19 includes, in general, an engine or motor piston 26 which is reciprocable in a motor cylinder 27, and includes a pump piston 28 which is reciprocable in a pump cylinder 29, the two pistons being directly connected by a rod 30. Connected to and extending upwardly from the motor piston 26 is a pilot rod 31, and connected to and extending downwardly from the pump piston 28 is a lower rod 32. As best shown in Fig. 5 of the drawings, the pump 19 is provided with a valve chamber 35 therein which communicates with the interior of the shock absorber 22, the latter being adapted to convey power oil from the power tubing 20 to the valve chamber in a manner to be discussed in more detail hereinafter. The pump 19 is provided with a pair of passages, indicated generally by the numerals 37 and 38, which respectively connect the valve chamber 35 to the upper and lower ends of the motor cylinder 27, each of the passages 37 and 38 preferably comprising a plurality of individual passages only one of which is shown in the drawings. The pump 19 is also provided with a discharge passage 39 which leads from the valve chamber 35 to the exterior of the pump and communicates with the interior of the production tubing 14, the passage 39 also preferably comprising a plurality of individual passages. Slidably disposed in the valve chamber 35 is an engine valve 40 of the piston type which is adapted to admit power oil alternately into opposite ends of the motor cylinder 27 through the passages 37 and 38, and which is adapted to connect opposite ends of the motor cylinder alternately to the discharge passage 39 leading to the production tubing 14. As will be apparent, when the piston valve 40, which is shown more or less diagrammatically, is in the position shown in Fig. 5 of the drawings, it admits power oil to the lower end 65 of the motor cylinder 27 through the passage 38 and connects the upper end thereof to the discharge passage 39, the piston valve being adapted to move downwardly to a position (not shown) wherein it admits power oil into the upper end 70 of the motor cylinder through the passage 37 and connects the lower end thereof to the discharge passage.

The foregoing discussion of the engine valve mechanism for controlling admission of the power oil to and discharge thereof from the motor

cylinder 27 is intended merely as a general description of its structure and operation since, per se, it forms no part of the present invention. For a detailed description of the structure and operation of a suitable engine valve mechanism, reference is made to my aforesaid Patent No. 2,134,174.

The general operation of the pump 19 is well known in the art, being described in detail in my Patent No. 2,134,174, and needs be described only briefly herein. The power oil, which is preferably clean crude oil, is delivered under pressure to the casing head 11 through a supply pipe 41 and flows downwardly through the power tubing 20 to the pump 19, the power oil flowing through the shock absorber 22 as will be discussed in more detail hereinafter. The power oil is admitted alternately into opposite ends of the motor cylinder 27 by the previously discussed engine valve mechanism so as to reciprocate the motor piston 28, the reciprocatory motion of the motor piston being communicated to the pump piston 28 by the intermediate rod 30. Well fluid from the body 16 is introduced alternately into opposite ends of the pump cylinder 29 by a suitable pump valve mechanism (not shown) and is discharged into the production tubing 14 as production fluid by the pump piston 28, the production fluid subsequently flowing upwardly through the production tubing to the surface. The production fluid flows from the production tubing 14 into a discharge pipe 42 which may lead to a point of use or storage.

With the foregoing general description of the structure and operation of an installation in which my shock absorber 22 may be incorporated in mind, the shock absorber itself will now be considered. In general, the device includes a movable fluid separating means which is exemplified as a piston 43, shown in Fig. 3, and which is reciprocable vertically in a cylinder 44, the lower end of this cylinder being adapted to receive power oil at operating pressure therein, and the upper end of this cylinder being adapted to receive production fluid therein. The shock absorber piston 43 is provided with a surface 47, shown in Fig. 2, which is adapted to be exposed to a fluid pressure greatly exceeding the pressures of the power oil and production fluid, the fluid acting on this surface of the piston being a liquid which is confined in a chamber 48 in the particular construction illustrated. The shock absorber 22 also includes fluid operated pumping means 49, shown in Fig. 3, carried by the piston 43 for maintaining the pressure and volume of the liquid in the chamber 48 at the desired value, the pumping means 49 being operated by the power oil periodically admitted into one end of the motor cylinder 27 as will be discussed in more detail hereinafter.

Considering the shock absorber 22 in more detail with particular reference to Figs. 2 to 5 of the drawings, it includes a housing which is formed in three sections 51, 52 and 53 for convenience in manufacture, the three sections of the housing being tubes arranged end-to-end in the particular construction illustrated. The uppermost tube 51 is threadedly connected at its upper end to a fitting 54 which, in turn, is threadedly connected to the lower end of the power tubing 20, the fitting 54 being provided with a passage 55 therethrough to admit power oil into the tube 51. The tubes 51 and 52 are threadedly connected by a fitting 56 and the tubes 52 and 53 are similarly connected by a fit-

ting 57, the tube 53 being threadedly connected at its lower end to a fitting 58 which, in turn, is threadedly connected to the upper end of the pump 19. As best shown in Figs. 2, 3 and 6 of the drawings, the fitting 56 connecting the tubes 51 and 52 is provided with a plurality of longitudinal passages 61 therethrough which conduct power oil from the tube 51 to the tube 52, and is provided with a depending tubular extension 62 which is spaced from the inner wall of the tube 52 to provide an annular passage 63 for the power oil. The fitting 57 connecting the tubes 52 and 53 is provided with an upwardly directed tubular extension 64 which is inserted into the lower end of the tubular extension 62 of the fitting 56 and which is spaced from the inner wall of the tube 52 to provide an annular passage 65 for the power oil, the fitting 57 being provided with a plurality of longitudinal passages 66 through which the power oil may flow from the annular passage 65 into the tube 53. The fitting 58 connecting the tube 53 to the pump 19 receives an insert 70 having a frusto-conical seat 71 which engages a frusto-conical surface 72 at the upper end of the pump, the insert 70 being provided with an annular shoulder 73 which is adapted to seat against an annular shoulder 74 on the fitting 58 to prevent upward movement of the insert. Rotation of this insert is prevented by key-like projections 75 thereon which are disposed in complementary keyways 76 in the fitting 58. The insert 70 is provided with an opening therethrough which receives the pilot rod 31, the diameter of this opening being greater than that of the pilot rod so as to provide an annular passage 77 communicating at one end with the interior of the tube 53 and at its other end with the valve chamber 35 in the pump 19. With the foregoing construction, it will be apparent that the power oil may flow from the power tubing 20 to the valve chamber 35 by way of the passage 55 through the fitting 54, the tube 51, the passages 61 through the fitting 56, the annular passages 63 and 65 around the tubular extensions 62 and 64 of the fittings 56 and 57, the passages 66 through the fitting 57, the tube 53, and the annular passage 77 through the insert 70. From the valve chamber 35, the power oil is admitted alternately into opposite ends of the motor cylinder 27 by the engine valve 40 in the manner previously discussed.

Referring particularly to Figs. 2 and 3 of the drawings, the depending tubular extension 62 of the fitting 56 forms the previously mentioned cylinder 44 for the shock absorber piston 43, the cylinder 44 being closed at its lower end by the upper end of the tubular extension 64 of the fitting 57, and being closed at its upper end by a tubular fitting 78 threaded into the upper end thereof. In the particular construction illustrated in the drawings, the chamber 48 for the liquid which acts on the surface 47 of the piston 43 has a bottle-like configuration and is provided with a neck 80 which is threaded into the upper end of the tubular fitting 78.

As best shown in Figs. 2 and 6 of the drawings, a plurality of radial passages 81 in the fitting 56 provide fluid communication between the production tubing 14 and the upper end of the cylinder 44 so that the pressure of the production fluid tends to move the piston 43 downwardly, and, as best shown in Fig. 3 of the drawings, a plurality of radial passages 82 in the tubular extension 62 of the fitting 56 provide fluid communication be-

tween the annular passages 63 for the power oil and the lower end of the cylinder 44 so that the pressure of the power oil tends to move the piston upwardly.

Referring particularly to Figs. 2 and 3 of the drawings, the surface 47 of the shock absorber piston 43, which surface is exposed to the pressure of the liquid in the chamber 48, is formed by the upper end of an upwardly extending, tubular stem 85 on the piston 43, the stem 85 extending through the tubular fitting 78 into the neck 80 of the bottle-like chamber 48 and being substantially sealed with respect to the fitting 78 by packing 86. The piston 43 is provided at its upper and lower ends with counterbores 87 and 88 which are connected by an intermediate bore 89, the counterbores 87 and 88 having threaded thereinto and being closed by tubular plugs 90 and 91, respectively. The stem 85 on the piston 43 extends through the tubular plug 90 and is provided with a head 92 thereon which is seated against the inner end of this plug. As will be discussed in more detail in the following paragraphs, the fluid operated pumping means 49 is disposed in the counterbore 87 and the bore 89 in the shock absorber piston 43 and is adapted to deliver a liquid, preferably oil obtained from the power oil supply, into the chamber 48, through the tubular stem 85 so as to maintain the pressure and volume of oil in the chamber 48 at the desired value.

Considering the pumping means 49 in more detail, the bore 89 in the piston 43 serves as a cylinder for an auxiliary piston 95, the cylinder 89 being closed at its upper end by an insert 96 which is seated against a shoulder 97 formed at the junction of the cylinder 89 and the counterbore 87, and being closed at its lower end by an insert 98 which is seated against a shoulder 99 formed at the junction of the counterbore 88 and the cylinder 89. The insert 98 is provided with a passage 100 therethrough which communicates with the interior of a downwardly extending tubular stem 101 on the piston 43, the stem 101 extending through the tubular plug 91 and being provided with a head 102 thereon which is seated against the outer end of the insert 98 and the inner end of the plug 91. The tubular stem 101 communicates with one end of the motor cylinder 27 in the pump 19 in a manner about to be described so that the fluid pressure obtaining in such end of the motor cylinder also obtains in the lower end of the cylinder 89 containing the auxiliary piston 95, the stem 101 communicating with the upper end of the motor cylinder in the particular construction illustrated although it may communicate with either end thereof.

Referring particularly to Figs. 3 and 4 of the drawings, the tubular stem 101 extends downwardly into a sectional liner 104 in the tubular extension 64 of the fitting 57. The liner 104 is provided with a plurality of longitudinal grooves 105 in its exterior surface, these grooves communicating with the interior of the liner at their lower ends through ports 106, and communicating with the interior of the liner at their upper ends through ports 107. The liner 104 includes a section 108 having an internal diameter which is greater than the external diameter of the tubular stem 101 so as to provide an annular space 109 which communicates with the ports 107 at the upper ends of the grooves 105. The tubular stem 101 is provided with a plurality of radial passages 110 therein which are adapted

to register with the annular space 109 to provide fluid communication between the interior of the tubular stem and the lower end of the liner 104 by way of the ports 106, the grooves 105 and the ports 107. It will be noted that as the shock absorber piston 43 moves downwardly, the radial passages 110 in the tubular stem 101 move out of registry with the annular space 109 to prevent such fluid communication, the reason for this being discussed hereinafter.

As best shown in Fig. 4 of the drawings, the fitting 57 is provided with a bore 112 at its lower end which communicates with the interior of the liner 104, a fitting 113 being threaded into the bore 112. Connected to the fitting 113 is the upper end of a conduit or tube 114 which is secured at its lower end to the insert 70 in the fitting 58 which connects the tube 53 of the shock absorber housing to the upper end of the pump 19. The tube 114 is provided with a coiled portion 115 intermediate its ends for convenience in assembling the shock absorber 22, the coiled portion of the tube 114 tending to seat the shoulder 73 on the insert 70 against the complementary shoulder 74 on the fitting 58 during assembly, as will be discussed in more detail hereinafter. The tube 114 communicates at its lower end with a passage 116 through the insert 70, the passage 116 communicating with a passage 117 in the pump 19 which, in turn, communicates with the passage 37 leading to the upper end of the motor cylinder 27 by way of the valve chamber 35 in the pump. It will be apparent that the fluid pressure obtaining in the upper end of the motor cylinder 27 is thus communicated to the lower end of the cylinder 89 in the shock absorber piston 43 and is thus applied to the lower end 103 of the auxiliary piston 95.

The auxiliary piston 95 is provided with an upwardly directed stem 121 which extends through a bore 122 in the insert 96 into a counterbore 123 therein, the stem making a tight fit with the bore 122. This construction provides the auxiliary piston with an annular surface 124 at its upper end which is equal in area to the difference in the cross-sectional areas of the piston and the stem 121. As best shown in Figs. 3 and 7, the annular surface 124 is exposed to the pressure of the production fluid by means of a plurality of passages 125 in the shock absorber piston 43 which communicate at their lower ends with the upper end of the cylinder 89 for the auxiliary piston 95 and which communicate at their upper ends with the upper end of the cylinder 44 for the piston 43.

Referring particularly to Fig. 3 of the drawings, the pumping means 49 includes check valves 133 and 134 interposed between the insert 96 and the head 92 on the tubular stem 85, the check valve 133 being provided with a passage 135 which terminates at one end in a seat 136 for a ball valve 137 and which communicates at its other end with an annular groove 138. The groove 138 registers with the upper ends of a plurality of passages 139 in the shock absorber piston 43, as best shown in Figs. 3 and 7 of the drawings. The passages 139 communicate at their lower ends with the lower end of the cylinder 44 so that power oil may flow from the lower end of the cylinder 44 to the check valve 133. The latter is provided with a passage 142 which terminates at one end in the seat 136 for the ball valve 137 and which communicates at its other end with a passage 143 in the check valve 134, the passage 143 terminating in a seat 144 for a ball valve 145.

From the seat 144, a passage 146 extends through the check valve 134 and communicates with the lower end of the tubular stem 85. The check valve 133 is provided with another passage 147 which communicates at one end with the passage 142 therein and which communicates at its other end with the counterbore 123 in the insert 96. It will be noted that the head 92 and the body of the check valve 133 are respectively provided with milled slots 148 and 149 therein at the upper ends of the passages 146 and 142, respectively, the widths of these slots being less than the diameters of the ball valves 145 and 137 to prevent seating of the ball valves at the upper ends of the passages mentioned.

The foregoing completes the description of the structure of the shock absorber 22 and the installation in which it is incorporated, and the operation of the shock absorber will now be considered, the operation of the pumping means 49 being considered first for convenience. It will be apparent that the upper end of the stem 121 on the auxiliary piston 95 is always exposed to a fluid pressure at least equal to the power oil pressure due to the fact that the ball valve 137 is arranged to be lifted off its seat 136 by the pressure of the power oil in the passage 135 in the check valve 133, the passage 135 communicating with the lower end of the shock absorber cylinder 44 through the annular groove 138 and the passages 139 as previously discussed. The annular surface 124 at the upper end of the auxiliary piston 95 is always exposed to the production fluid pressure through the passages 125 connecting the upper end of the cylinder 89 to the upper end of the cylinder 44. Thus, the auxiliary piston 95 is always subjected to a downward force which is equal to the product of the area of the annular surface 124 and the production fluid pressure plus the product of the area of the upper end of the stem 121 and a fluid pressure at least equal to the power oil pressure.

As previously discussed, the lower end of the cylinder 89 for the auxiliary piston 95 communicates with the upper end of the motor cylinder 27 in the pump 19 so that the same fluid pressure obtains in the lower end of the cylinder 89 as obtains in the upper end of the motor cylinder, which fluid pressure varies between the power oil pressure and the production fluid pressure under the control of the engine valve 40. Thus, the auxiliary piston 95 is subjected to an upward force which alternates between a value equal to the product of the cross-sectional area of the piston and the production fluid pressure and a value equal to the product of the cross-sectional area of the piston 89 and the power oil pressure. Consequently, when the lower end 103 of the auxiliary piston 95 is exposed to the power oil pressure, the auxiliary piston will move upwardly in its cylinder 89, and when it is exposed to the production fluid pressure, as shown in Fig. 5, the auxiliary piston will move downwardly in its cylinder. Since the pressure applied to the lower end 103 of the auxiliary piston 95 alternates between the power oil pressure and the production fluid pressure, a reciprocatory motion of the auxiliary piston results to pump oil from the power oil supply into the chamber 48.

Considering the manner in which the auxiliary piston 95 pumps oil into the chamber 48, it will be apparent that as the auxiliary piston moves downwardly, oil from the power oil supply flows into the counterbore 123 in the insert 96 past the ball valve 137, flow from the chamber 48 during

5 downwardly movement of the auxiliary piston being prevented by the ball valve 145. During upward movement of the auxiliary piston 95, the stem 121 forces at least a part of the oil in the counterbore 123 past the ball valve 145 and into the chamber 48 through the tubular stem 85, flow back into the passages leading to the lower end of the shock absorber cylinder 44 being prevented during upward movement of the auxiliary piston by the ball valve 137. Thus, it will be apparent that for each complete cycle of movement of the auxiliary piston 95, a quantity of oil from the power oil supply is introduced into the chamber 48 to maintain the desired pressure and volume therein, the quantity introduced being sufficient to replace any oil escaping from the chamber as by leakage past the packing 86 encircling the tubular stem 85.

It will be understood that although the fluid operating pumping means 49 is shown as adapted to pump oil from the power oil supply into the chamber 48, it may be designed to pump production fluid thereinto, or to pump fluid from an independent source thereinto. However, I prefer to employ oil from the power oil supply as it is normally cleaner than the production oil.

For reasons which will be discussed in more detail hereinafter, the pressure in the chamber 48 is maintained at a high value, e. g., preferably at a value of the order of magnitude of from 30 25,000 to 50,000 pounds per square inch. As will be apparent to those skilled in the art, any desired value for the pressure in the chamber 48 may be attained by suitably relating the areas 35 of the auxiliary piston 95 and the stem 121 thereon to the power oil and production fluid pressures. For example, if the difference between the power oil and production fluid pressures is 40 1,250 pounds per square inch, a construction wherein the ratio of the area of the annular surface 124 of the auxiliary piston 95 to the cross-sectional area of the stem 121 thereon is 20:1 45 will produce a pressure of approximately 25,000 pounds per square inch in the chamber 48. In other words, the pumping means 49 will have an amplification factor of twenty in this example.

Considering the over-all operation of the shock absorber 22, it will be apparent that the pressure of the power oil in the lower end of the cylinder 44 tends to move the shock absorber piston 48 upwardly while the pressure of the production fluid in the upper end of the cylinder 44 and the pressure of the oil in the chamber 48 tend to move the shock absorber piston downwardly. 50 The piston 48 is balanced when normal operating conditions for the pump 19 prevail, but, if the relative fluid pressures obtaining in the production and power tubings 14 and 20 vary, the piston 48 becomes unbalanced and moves either upwardly or downwardly in its cylinder 44, depending upon the direction of unbalance. If, for example, the unbalanced force acts upwardly, the energy producing the force is absorbed by compression of the oil in the chamber 48 and also by compression of the production fluid. Conversely, if the unbalanced force acts downwardly, the energy producing same is absorbed by compression of the power oil. Thus, variations in the relative fluid pressures obtaining in the production and power tubings 14 and 20 which might otherwise produce hydraulic shock loads having detrimental effects are absorbed.

Such variations in the relative fluid pressure may arise from various sources. For example, if 75 air or gas is present in the pump cylinder 29, the

motor piston 26 and the pump piston 28 may, as previously discussed, accelerate to an excessive speed so that a pressure surge in the production tubing 14 may result when the pump piston strikes solid well fluid. Also, pressure pulsations may be produced in the fluids in the production tubing 14 and the power tubing 20 due to the reciprocatory motion of the motor and pump pistons 26 and 28 as previously discussed.

Considering in more detail the manner in which pressure pulsations resulting from the reciprocatory motion of the motor and pump pistons 26 and 28 are absorbed, and referring particularly to Fig. 9 of the drawings, the numerals 155 and 156 indicate oscillograph curves showing respectively, typical pressure pulsations encountered in the power oil and production fluid columns when a pump such as the pump 19 is used without the shock absorber 22. It will be noted that the power oil pressure rises at the ends of the stroke of the motor and pump pistons 26 and 28 (see curve 155) and that the pump discharge pressure or production fluid pressure drops at the same time (see curve 156), the pressure pulsations in the two columns being of approximately the same magnitude and of opposite sign. The rise in pressure in the power tubing 20 and the drop in pressure in the production tubing 14 cause the shock absorber piston 43 to move upwardly against the pressure of the oil in the chamber 48 so that the energy producing such movement is absorbed by compression of the oil in this chamber, and also by compression to some extent of the production fluid. The net result is that the pressure in the power tubing 20 is decreased and the pressure in the production tubing 14 is increased, the resultant pressure in the two columns being approximately as indicated by the oscillograph curve 157 in Fig. 11. Thus, it will be apparent that, in effect, the shock absorber 22 causes the rise in power oil pressure and the drop in production fluid pressure to cancel out, which is an important feature of the invention.

It will be recalled that the radial passages 110 in the tubular stem 101 on the shock absorber piston 43 are adapted to move out of registry with the annular space 109 after a predetermined downward movement of the shock absorber piston. More specifically, the passages 110 move out of registry with the annular space 109 when the piston 43 moves below its neutral or mid-position. This cuts off communication between the lower end of the cylinder 89 containing the auxiliary piston 95 and the upper end of the motor cylinder 27 so as to interrupt operation of the pumping means 49. With this construction, the pumping means 49 will operate only until the desired pressure is built up in the chamber 48, which pressure balances the shock absorber piston 43 and moves it to its mid-position. Consequently, if the shock absorber piston moves downwardly below its mid-position, due, for example, to an increase in production fluid pressure, the operation of the pumping means 49 is interrupted to prevent its pumping more liquid into the chamber 48 so that the shock absorber piston may return to its mid-position when the production fluid pressure returns to normal.

As previously mentioned, it is desirable to maintain the pressure in the chamber 48 at a high value, the reason for this being that the amount of energy which a liquid is capable of absorbing as it is compressed is directly pro-

portional to the pressure of the liquid. The relationship between the variables involved may be expressed by the following equation:

$$W = PdP/K$$

5 In this equation,

W=the energy absorbed per unit volume of the liquid,

P=the pressure of the liquid,

10 dP=the increase in pressure of the liquid, and K=the bulk modulus of the liquid.

It will thus be apparent that the higher the pressure maintained in the chamber 48 by the pumping means 49, the greater will be the 15 energy absorbed by compression of the liquid to a given extent, which is an important feature of my invention.

Another feature of the invention resides in the 20 provision of a shock absorber wherein the value of dP in the foregoing equation, as well as the value of P therein, is amplified, this being accomplished by making the cross-sectional area of the stem 85 which extends into the chamber 25 48 small as compared to the area of the shock absorber piston 43 exposed to the power oil pressure. If an area ratio of 10, for example, is employed, it will be apparent that the increase in dP resulting from a given increase 30 in the power oil pressure, i. e., the pressure increase in the chamber 48 resulting from a given increase in the power oil pressure, will be ten times the increase in the power oil pressure to provide an amplification factor of ten for the shock absorber piston.

35 As will be apparent from the foregoing equation, since the energy absorbing capacity of the shock absorber varies with both P and dP, a very large capacity can be obtained with 40 a small volume of liquid in the chamber 48 by making both P and dP large. Thus, if the shock absorber piston 43 and the pumping means 49 are provided with amplification factors of ten, the energy absorbing capacity of the device will 45 be increased by a factor of one hundred, which is an important feature of the invention.

It will thus be apparent that by employing the 50 pumping means 49 to convert a relatively low pressure into a relatively high value for P in the chamber 48, and by converting a relatively low pressure increase in the power oil pressure (or, conversely, a relatively low decrease in the 55 production fluid pressure) into a relatively high value for dP in the chamber 48, a large energy absorbing capacity may be attained with a relatively small volume of liquid in the chamber 48, which is an important advantage of the invention. Thus, the volume of the chamber 48 may be much less than that of an air chamber, for 60 example, having an equivalent energy absorbing capacity.

As previously indicated, the conduit or tube 114 which provides fluid communication between the motor cylinder 27 of the pump 19 and the pumping means 49 of the shock absorber 22 is provided with the coiled portion 115 to facilitate assembly of the shock absorber, the coiled portion 115 of the tube rendering the tube flexible and serving as a resilient means for performing 70 a function to be described. Considering the manner in which the flexible tube 114 facilitates assembly of the shock absorber 22, one step in the assembly of the device involves threading the lowermost tube 53 of the shock absorber housing 75 onto the fitting 58 which connects the shock

absorber to the pump 19 (prior to threading this fitting on the upper end of the pump). Subsequently, the flexible tube 114 is inserted through the fitting 58 into the tube 53 and the keys 75 on the insert 70 are inserted into the keyways 76 therefor, the lower end of the tube 114 previously having been permanently connected to the insert 70, as by soldering, for example. After the tube 114 has been inserted into the tube 53 of the shock absorber housing, the fitting 113 of the shock absorber housing, the fitting 113 is threaded into the bore 109 of the fitting 57 is assembled to secure the upper end of the tube 114 to the fitting 57, this being done prior to threading the fitting 57 into the upper end of the tube 53. The coiled portion 115 of the tube 114 is adapted to be extended during this operation. After the upper end of the tube 114 has been connected to the fitting 57 by means of the fitting 113, the insert 70 is pulled downwardly so that the keys 75 thereon disengage the keyways 76 in the fitting 58, such downward movement being permitted by extension of the coiled portion 115 of the tube 114. With the insert 70 pulled downwardly in this manner, it may rotate relative to the fitting 58 to permit threading the fitting 57 for connecting the tubes 52 and 53 of the shock absorber housing into the upper end of the tube 53 of the housing. Subsequently, the insert 70 is rotated until the keys 75 thereon are aligned with the keyways 76 in the fitting 58. Since the insert 70 was previously pulled down to stretch the coiled portion 115 of the tube 114, the coiled portion of the tube will then pull the insert 70 upwardly so that the keys 75 enter the keyways 76 and so that the shoulder 73 on the insert seats against the shoulder 74 on the fitting 58. The insert 70 will then rotate with the fitting 58 due to the action of the keys 75 in the keyways 76 so that the fitting 58 may be threaded onto the upper end of the pump 19.

It will be understood that the fitting 57 for connecting the tubes 52 and 53 of the shock absorber housing may be threaded into the upper end of the tube 53 in the foregoing manner either before or after having been assembled with the components of the shock absorber 22 thereabove.

Although I have disclosed an exemplary embodiment of my invention herein for purposes of illustration, I do not intend to be limited specifically thereto since various changes, modifications and substitutions may be incorporated in the embodiment disclosed without necessarily departing from the spirit of the invention. For example, although I have disclosed the pressure in the chamber 48 as opposing the power oil pressure, it may be employed to oppose the production fluid pressure. Similarly, although I have shown the pumping means 49 as being adapted to pump oil from the power oil supply into the chamber 48, it may pump liquid from another source thereinto. Various other changes may also be made without departing from the spirit of the invention. Consequently, I hereby reserve the right to all changes, modifications and substitutions as properly come within the scope of the invention as set forth in the appended claims.

I claim as my invention:

1. In a fluid operated pumping unit, the combination of: a pump adapted to be operated by a first fluid under pressure to pump a second fluid under pressure; a shock absorber provided with movable fluid separating means therein; means for admitting the first fluid into said shock absorber on one side of said fluid separating means;

means for admitting the second fluid into said shock absorber on the opposite side of said fluid separating means; and means in said shock absorber for applying to at least a portion of one of said sides of said fluid separating means a fluid pressure exceeding the pressures of the first and second fluids.

2. A fluid operated pumping unit, comprising: a pump adapted to be operated by a first fluid under pressure to pump a second fluid under pressure; a cylinder; a piston in said cylinder; means for exposing at least a portion of one end of said piston to the pressure of the first fluid; means for exposing at least a portion of the opposite end of said piston to the pressure of the second fluid; and means for applying to at least a portion of one of said ends of said piston a fluid pressure greatly exceeding the pressures of the first and second fluids.

3. In an apparatus for pumping fluid from a well, the combination of: a fluid operated pump in the well; a first tubing extending into the well and connected to said pump, said first tubing being adapted to convey operating fluid to said pump to operate same; a second tubing extending into the well and connected to said pump, said second tubing being adapted to convey from said pump production fluid discharged thereby; and a shock absorber, said shock absorber including movable fluid separating means provided with first and second surfaces on opposite sides thereof and provided with a third surface on one of said sides thereof, said shock absorber including means for exposing said first surface of said fluid separating means to fluid pressure obtaining in said first tubing, including means for exposing said second surface of said fluid separating means to fluid pressure obtaining in said second tubing, and including means for exposing said third surface of said fluid separating means to a fluid pressure greatly exceeding the fluid pressures obtaining in said first and second tubings.

4. In a shock absorber for use in a well pumping apparatus which includes a fluid operated pump having first and second tubings connected thereto, the first tubing being adapted to convey operating fluid to the pump to operate same and the second tubing being adapted to convey from the pump production fluid discharged thereby, the combination of: movable fluid separating means having first and second surfaces on opposite sides thereof and having a third surface on one of said sides thereof; means for exposing said first surface of said fluid separating means to fluid pressure obtaining in the first tubing; means for exposing said second surface of said fluid separating means to fluid pressure obtaining in the second tubing; and means for exposing said third surface of said fluid separating means to a fluid pressure greatly exceeding the fluid pressures obtaining in the first and second tubings.

5. In a device for absorbing pressure variations in first and second fluids, the combination of: movable fluid separating means having first and second surfaces on opposite sides thereof and having a third surface on the same side thereof as said second surface, the area of said third surface being small as compared to the areas of said first and second surfaces; means for applying the pressure of the first fluid to said first surface of said fluid separating means; means for applying the pressure of the second fluid to said second surface of said fluid separating means; and means for applying to said third surface of said fluid separating means a fluid pressure ex-

ceeding the pressures of the first and second fluids.

6. A device as set forth in claim 5 wherein the product of the pressure of the first fluid and the area of said first surface substantially equals the product of the pressure of the second fluid and the area of said second surface plus the product of the pressure applied to said third surface and the area of said third surface.

7. In a device for absorbing pressure variations in first and second fluids, the combination of: a housing; movable fluid separating means in said housing, said fluid separating means having first and second surfaces on opposite sides thereof and having a third surface on one of said sides thereof; means for applying the pressure of the first fluid to said first surface of said fluid separating means; means for applying the pressure of the second fluid to said second surface of said fluid separating means; a source of fluid pressure; means for applying to said third surface of said fluid separating means the fluid pressure obtaining at said source; and means in said housing for maintaining fluid pressure at said source.

8. A device as set forth in claim 7 wherein the means last mentioned comprises pumping means for delivering fluid under pressure to said source.

9. A device as set forth in claim 8 wherein said pumping means is operable by the first and second fluids.

10. A device as set forth in claim 7 wherein the means last mentioned is carried by said movable fluid separating means.

11. In a device of the character described, the combination of: a cylinder; a piston reciprocable in said cylinder; a source of fluid pressure; means for applying to at least a portion of the area of one end of said piston the fluid pressure obtaining at said source; and pumping means including a plunger carried by and movable relative to said piston for maintaining fluid pressure at said source.

12. A device as set forth in claim 11 wherein said pumping means is fluid operated, said device including means for connecting one side of said plunger to a source of alternating pressure.

13. In a shock absorber, the combination of: a cylinder; a piston reciprocable in said cylinder; a chamber for a fluid under pressure connected to said cylinder; pumping means including a plunger carried by and movable relative to said piston for maintaining fluid pressure in said chamber; and means for applying the fluid pressure in said chamber to at least a portion of one end of said piston.

14. A shock absorber as set forth in claim 13 wherein said piston is provided with a tubular stem which extends into said chamber, said stem communicating at one end with the interior of said chamber and at its other end with an outlet of said pumping means.

15. A shock absorber as set forth in claim 14 wherein said pumping means is fluid operated, passage means being provided for connecting one end of said plunger to a source of alternating fluid pressure.

16. In a shock absorber, the combination of: a main cylinder; a main piston reciprocable in said main cylinder and provided with an auxiliary cylinder therein; a chamber for a fluid under pressure connected to said main cylinder; fluid operated pumping means carried by said main piston and communicating with the in-

terior of said chamber for maintaining fluid pressure in said chamber, said pumping means including an auxiliary piston reciprocable in said auxiliary cylinder; means for applying an alternately increasing and decreasing fluid pressure to one end of said auxiliary piston; and means for applying the fluid pressure in said chamber to at least a portion of one end of said main piston.

17. A shock absorber as set forth in claim 16 wherein said main piston is provided with a tubular stem which extends into said chamber, said stem communicating at one end with the interior of said chamber and at its other end with said auxiliary cylinder.

18. In a fluid operated pumping unit, the combination of: a fluid operated pump provided with a motor cylinder having a motor piston reciprocable therein and provided with means for periodically admitting an operating fluid under pressure into one end of said motor cylinder; a shock absorber cylinder; a shock absorber piston reciprocable in said shock absorber cylinder; a chamber for a fluid under pressure; fluid operated pumping means for maintaining fluid pressure in said chamber; passage means communicating at one end with said one end of said motor cylinder for conveying operating fluid to said pumping means to operate same; and means for applying the fluid pressure in said chamber to at least a portion of one end of said shock absorber piston.

19. A fluid operated pumping unit as defined in claim 18 wherein said shock absorber piston is provided with an auxiliary cylinder therein, wherein said pumping means includes an auxiliary piston reciprocable in said auxiliary cylinder, and wherein said passage means communicates at its other end with one end of said auxiliary cylinder.

20. In a shock absorber, the combination of: a cylinder; a piston reciprocable in said cylinder; a chamber for a fluid under pressure; an axially extending, tubular stem on said piston, the cross-sectional area of said stem being exposed to the fluid pressure in said chamber and being small as compared to the cross-sectional area of one end of said piston; and means for delivering fluid under pressure to said chamber through said tubular stem.

21. In a fluid operated well pumping device, the combination of: a first fluid operated pump adapted to be disposed in a well so as to pump well fluid therefrom, and having a first cylinder and a first piston in said cylinder; a second fluid operated pump adapted to be disposed in the well, said second pump having a second cylinder and a second piston therein; and passage means for connecting one end of said second cylinder in continuous fluid communication with one end of said first cylinder.

22. In a device adapted to be used with a fluid operated pump in a well, the pump being operated from a source of operating fluid under high pressure, the combination of: a chamber filled with liquid under fluid pressure higher than that of said source; a movable wall, one side of which is adapted to communicate with said source and be exposed to the fluid pressure thereof; plunger means connected to the other side of said wall and extending into said chamber and movable with respect thereto, said plunger means having an effective cross-sectional area exposed to the fluid pressure in said chamber which is substantially smaller than the effective cross-sectional area of said one side of said wall exposed to the

fluid pressure of said source; and pumping means including a plunger carried by and movable relative to said movable wall for delivering liquid to said chamber to maintain said higher fluid pressure therein

23. In a fluid operated pumping device, the combination of: a fluid operated pump having a fluid port therein in one end thereof; a tubular member adapted to be threadedly connected to said end of said pump; a fitting adapted to be 10 threadedly connected to the other end of said member, said fitting having a fluid passage therein; and a flexible fluid conduit in said member for connecting said port and said passage, said flexible fluid conduit including a coiled portion.

24. In a fluid operated pumping device, the combination of: a fluid operated pump having a fluid port therein in one end thereof; a tubular member adapted to be threadedly connected to said end of said pump; a fitting adapted to be 15 threadedly connected to the other end of said member, said fitting having a fluid passage therein; a flexible fluid conduit in said member for connecting said port and said passage, said flexible fluid conduit including a coiled portion; and means for releasably connecting said conduit to said pump.

25. In a shock absorber adapted to be connected to a fluid operated pump, the combination of: a tubular member adapted to be threadedly connected at one end to one end of the pump; a fitting adapted to be threadedly connected to the other end of said member; an insert adapted to move in said member from said one end thereof toward said other end thereof from a first position to a second position; means for limiting movement of said insert beyond said second position; and resilient conduit means in said member adapted to be rigidly connected at one end to said insert and at its other end to said fitting for biasing said insert toward said second position.

26. A shock absorber as set forth in claim 25 wherein said insert is rotatable relative to said member when it is in its said first position so as to permit rotation of said fitting relative to said member, whereby to permit threadedly connecting said fitting to said other end of said member.

27. A shock absorber as set forth in claim 26 including means for preventing rotation of said insert relative to said member when it is in its said second position.

28. In a shock absorber for absorbing pressure variations in a first fluid normally of one pressure and a second fluid normally of another, lower pressure, the combination of: a cylinder; a piston in said cylinder having on one side thereof a first surface and having on the other side thereof second and third surfaces, the area of said third surface being less than the areas of said first and second surfaces; means including a passage communicating with said cylinder on said one side of said piston for exposing said first surface to the first fluid; means including a passage communicating with said cylinder on said other side of said piston for exposing said second surface to the second fluid; and means for exposing said third surface to a third fluid of a pressure sufficient to balance 70

the normal pressure force differential applied to said piston by the first and second fluids, including a chamber confining said third fluid so that said third fluid acts resiliently on said third surface to absorb any differences between said normal pressure force differential and abnormal pressure force differentials resulting from variations in the pressures of the first and second fluids from normal.

29. In an apparatus for pumping fluid from a well, the combination of: a fluid operated pump in the well; a first tubing extending into the well and connected to said pump, said first tubing being adapted to convey operating fluid to said pump to operate same; a second tubing

15 extending into the well and connected to said pump, said second tubing being adapted to convey from said pump production fluid discharged thereby; and a shock absorber, said shock absorber including movable fluid separating means provided with a first surface on one side thereof and second and third surfaces on the opposite side thereof, the area of said third surface being less than the areas of said first and second surfaces, said shock absorber including means

20 for exposing said first surface of said fluid separating means to fluid pressure obtaining in said first tubing, including means for exposing said second surface of said fluid separating means to fluid pressure obtaining in said second tubing, and including means for exposing said third surface of said fluid separating means to a third fluid, said shock absorber further including a chamber which confines the third fluid so that

25 said fluid separating means varies the pressure in said chamber in response to variations in the fluid pressures obtaining in said first and second tubings to balance the fluid pressures applied to said fluid separating means.

30. In a shock absorber for a fluid-operated pump adapted to be operated by fluid at one generally constant pressure level and to discharge fluid at another generally constant pressure level, the combination of: movable means for separating the fluid at said one generally constant pressure level from the fluid at said other generally constant pressure level; and means for applying to said movable means in a direction opposing the higher of said pressure levels the pressure of a third fluid, including a chamber for confining said third fluid.
